UNITED STATES PATENT OFFICE.

ALRAH B. EDWARDS, OF COVINGTON, KENTUCKY, ASSIGNOR, BY MESNE ASSIGNMENTS, TO SHORTWRITER COMPANY, OF WILMINGTON, DELAWARE AND CHICAGO, ILLINOIS, A CORPORATION OF DELAWARE.

STENOGRAPHIC WRITING-MACHINE.

1,293,739.

Specification of Letters Patent. Patented Feb. 11, 1919.

Application filed June 5, 1915. Serial No. 32,265.

To all whom it may concern:

Be it known that I, ALRAH B. EDWARDS, a citizen of the United States, and a resident of Covington, in the county of Kenton and State of Kentucky, have invented certain new and useful Improvements in Stenographic Writing-Machines, and I do hereby declare that the following is a full, clear, and exact description thereof, reference 5 being had to the accompanying drawings, and to the characters of reference marked thereon, which form a part of this specification.

This invention relates to improvements in 15 the art of stenographic writing and refers more particularly to improvements in writing machines which employ a so-called "single case" keyboard, and the invention consists in the arrangement and combination 20 of elements shown in the drawings and hereinafter described and set forth in the appended claim.

Among the objects of the invention is to 25 greatly multiply the capacity of a writing machine employing a "single case" keyboard without increasing the number of keys in the keyboard and corresponding type on the typeheads.

A further object of the invention is to 30 differentiate the selected letters of the alphabet employed on the keyboard so that each character may be used in its natural significance to designate a letter or a code character of the system in one use thereof, and to 35 designate an entirely different character in another use thereof, means being provided to visually differentiate the significance of the characters on the printed record, so that no possible confusion can occur in reading a 40 record made up of characters so differentiated.

Another object of the invention is to simplify the code representations for missing letters of the alphabet which do not appear 45 on the face of the keyboard. By our improved arrangement we are able to represent almost every missing letter by operating but a single key, and never more than two keys. In order to represent missing letters all 50 other single case machines known to the art employ from three to six letters struck in combination to represent a missing letter which necessarily places a burden on the

mind of the operator in writing and likewise the one who reads the written record. 55

Another object of the invention is to place the control of the ribbon shifting mechanism directly under the hands of the operator, and, being so placed, is easily and quickly operated without it being necessary 60 to move the hands from the regular operating positions.

A further object of the invention is to provide a ribbon guide and shifting mechanism that will carry a two-color ribbon 65 evenly and regularly in front of a row of type which are operated to print simultaneously in a straight line, the ribbon guides being spaced apart a distance greater than the total length of a line of type which may 70 be printed at one time.

Another object of the invention is to provide a ready, simple and accessible lock for a two-color ribbon shifting device when shifted from one field of the ribbon to another. 75

In practically carrying my invention into practice or applying my improvements to a writing machine, I provide a "single case" keyboard which bears a selected number of 80 the letters of the alphabet or other characters if desired, the keys of the keyboard being arranged in groups to facilitate the manipulation of the keys by the fingers and thumbs of the two hands of the operator, 85 whereby a number of keys may be simultaneously depressed in certain combinations to compose in like combinations the type imprints on the record sheet or slip, in a manner familiar in stenographic writing 90 practice. In addition thereto, there is provided a two-color ribbon through which the imprints are made by the type, with means for shifting the same to present the two fields of color alternately to the printing 95 line, so that the type character appropriated to each key may be written in either of the colors of the ribbon. In the practical adaptation of my system, the characters when printed in one color as, for instance, black, may be used in the natural significance of said characters or a selected significance thereof based on a code system of writing, and when printed in another color as, for instance, red will designate entirely 100 different characters as, for instance, numer-

105

als, punctuation marks, or prefixes and suffixes.

I have shown in the drawings one practical mechanism for carrying my invention into effect, although it will be understood that the invention is capable of being practised by writing mechanism differing in structural details from that herein shown.

As shown in the drawings:—

10 Figure 1 is a plan view, diagrammatic in its nature, showing one form of keyboard and the related keybars of a writing machine to which my invention may be applied.

15 Fig. 2 is a fragmentary transverse, longitudinal vertical section showing certain elements of the writing mechanism and showing also the two color ribbon shifting device.

20 Fig. 3 is a detail of the ribbon shift guide. Fig. 4 is a detail illustrating the manner of locking the ribbon shift mechanism.

The keyboard shown in Fig. 1 of the drawings is divided into three groups of 25 keys designated by A, B and C. The groups A and B are arranged at the sides of the machine and symmetrically with respect to the central group C which preferably extends forwardly from the side groups.

30 The keys of groups A and B bear certain consonants of the alphabet which are selected with respect to their frequent occurrence in written language and are arranged relatively to each other with respect to the 35 facility or ease of combining them to produce or represent missing letters, compound sounds or prefixes and suffixes of words, the letters of group A being thus combined to represent prefixes and the letters of group 40 B being combined to produce suffixes of words. The keys of the group C bear certain vowels of the alphabet.

In accordance with my invention, and as it will be more fully understood when the 45 mechanical adaptation of the invention is hereinafter described, the character of each key of each group may be printed in differentiating colors by shifting the two color ribbon employed, so that each of said characters when printed in one color may be used in its natural significance or to present a compound sound of which the letter is suggestive, and when printed in another color, will acquire an entirely different significance which may be used arbitrarily to 50 represent numerals, punctuation marks or prefixes and suffixes. Moreover the characters of the several groups may be written simultaneously to print code characters of 55 a given or selected code significance in either one or two colors.

In stenographic writing machines as heretofore constructed it has not been practical to employ all of the vowels of the alphabet 60 without encumbering the machine with a

number of shift keys, much less to designate the various vowel variations which, in the alphabet, are represented by a single letter: In accordance with my improved system it becomes possible to double the capacity of 70 the machine with respect to the printing of the vowels, when printed separately, inasmuch as each vowel character will represent one sound when printed in one color and will represent a variant of that sound when 75 printed in another color. In addition to the arrangement shown permits the vowel characters to be written in combinations to supply practically all the vowel sounds of the language including the different variations of the primary vowel sounds. This 80 enables me to represent the exact spelling, sound and pronunciation of any unusual technical words or proper names.

Referring now to Figs. 2, 3 and 4, which 85 show a practical form of mechanism by which my improved system of writing may be adapted to standard stenographic writing machines the same is made as follows:

10 designates the platen of the machine 90 about which the strip of paper 11 is carried to receive printed impressions from the type. The strip of paper 11 is unwound from a reel 12 which is supported on the machine frame 14 and is guided to the platen by the 95 aid of a guide roll 15.

The type bars 16 which carry the type-heads are spring mounted and are connected in an suitable or preferred manner to key bars 18 which are spring mounted in the 100 frame and carry at their front ends keys 19 which bear the letters or characters of the groups A, B and C. The particular construction and arrangement of the key levers and type levers and the manner of operating 105 the type levers is like that illustrated and described in my prior application for U. S. Letters Patent, Serial No. 736,318, filed on the 12th day of December, 1912, and need not be herein more specifically referred to. 110

20, 20 designate ribbon guides through which the two colored ribbon 21 is threaded so as to hold the same in front of the platen in position to be struck by the type. The said ribbon guides are carried by the forward ends of curved vertically swinging arms 22 that are pivoted at their rear ends to lugs 23 mounted on the machine frame, whereby the forward ends of said arms and the ribbon guides carried thereby are capable of being raised and lowered relatively to the axis of the platen to present the differently colored transverse portions of the ribbon to the type. 115

The said ribbon shifting arms 22 are 120 adapted to be swung about their pivots to raise and lower the ribbon guides and to present different fields of the ribbon to the type by means of a link 25 which is pivoted 125 at its lower end of a vertically swinging 130

shift bar 26 that is pivoted at 27 to the machine frame and is upheld by a spring 28, and said link is connected at its upper end to the horizontal member 29 of a yoke, the 5 arms 30 of which are loosely connected to the ribbon guide arms 22. The shifting bar 27 is provided at its forward end with a shift key 32 which preferably lies just in rear of and slightly above the group of keys C 10 so that it may be readily actuated by a thumb of the operator. It will thus be understood that the ribbon may be shifted without the necessity of the operator changing his hands from their normal key operating 15 position. This arrangement of the ribbon shift key may be used in other writing machines than stenographic writing machines. The shifting bar is extended through the usual guide comb 33 which 20 limits its movements in both directions and determines the position of the ribbon.

The swinging movement of the ribbon shifting bar is less than that of the type bars so that when a character or combination of 25 characters is to be printed in a color which requires the shifting of the ribbon, the said ribbon is shifted with a less movement of its key bar than that of the key bars for actuating the type so that the ribbon will always 30 be fully shifted when the type strike the ribbon at the printing line.

To lock the ribbon shift operating bar so as to hold the ribbon in its abnormal position as, for instance, to print a number of 35 impressions from the red field of the ribbon, I provide a locking device such as illustrated in Fig. 4. This locking device is made as follows: The key 32 of the ribbon shifting mechanism is carried by the upper end of a 40 stem 35 which is pivoted to the upstanding end 36 of the shift key bar by a pivot pin 37. The key stem is provided on its front edge with a notch 38 adapted to engage the edge of an inwardly extending thin stop plate 39

which is attached to the front member of the 45 machine frame which extends between the central keys of the group C. With this construction, if it is desired to lock the ribbon shifting mechanism the key stem 35 is shifted rearwardly at its upper end when 50 the key is depressed so as to bring the notch thereof into locking engagement with the locking plate 39. When the key is again shifted to bring the ribbon into normal position the notched stem is released from the 55 locking plate and the controlling spring of the shifting bar restores the shifting mechanism to normal position. The key stem is fitted to the upstanding arm of the bar in any suitable manner to normally hold the 60 stem in normal position as, for instance, by providing a friction fit between the parts. Said ribbon shifting mechanism lock may be used on other types of writing machines than stenographic writing machine. 65

It will be noted that the ribbon guides are spaced a distance apart somewhat greater than the total length of a line of type which may be written in combination which includes the type at both side limits of the keyboard or a full line of the type when all the keys are depressed at one time. 70

I claim as my invention:—

In a stenographic writing machine a ribbon shift comprising a pair of pivotally mounted arms having means to support the ribbon, a shift key lever, a yoke connected to said arms and a link connecting said shift key lever and yoke. 75

In testimony, that I claim the foregoing as my invention I affix my signature in the presence of two witnesses, this 28th day of May, A. D. 1915. 80
